UNITED STATES PATENT OFFICE.

REGINALD A. FESSENDEN, OF BROOKLINE, MASSACHUSETTS, ASSIGNOR TO SUBMARINE SIGNAL COMPANY, OF PORTLAND, MAINE, A CORPORATION OF MAINE

SUBMARINE SIGNALING.

Application filed March 23, 1918. Serial No. 224,288.

To all whom it may concern:

Be it known that I, REGINALD A. FESSENDEN, of Brookline, in the county of Norfolk and State of Massachusetts, a citizen of the 5 United States, have invented new and useful Improvements in Submarine Signaling, of which the following is the specification.

My invention relates to the generation and utilization of elastic impulses and more particularly to submarine signaling, and still more particularly to the detection of submarines.

The figure forming a part of this specification, shows partly diagrammatically, 15 means adapted for carrying out my invention.

My invention has for its object the increased efficiency in the generation and utilization of elastic impulses and in submarine 20 signaling and in the detection of submarines, and other similar bodies.

Referring to the figure, 11 is a tank containing fluid, for example a fuel oil tank or a water tank, preferably extending the full 25 width of the vessel 23 and preferably intermediate between the bow of the vessel and the stern of the vessel, as the separation from the bow tends to reduce the water noise and the separation from the stern tends to 30 reduce the machinery noises, and especially if there are other compartments, such as 12 and 13, inserted between the tank 11 and the bow of the vessel and between the tank 11 and the machinery compartment of the vessel, as these compartments 12 and 13 act as 35 sound screens.

An additional advantage of having the tank in this intermediate location and also 40 extending from one side to the other of the vessel, is that on account of the bending of the sound waves, signals can be sent and heard and submarines detected ahead or astern substantially equally as well, or better than abeam.

The tank 11 need not be a single tank but 45 may be divided up into a number of compartments, for example by the horizontal bulkhead 14. This horizontal bulkhead 14 is preferably several feet below the water 50 line of the vessel and is preferably sound proof, as it has been found that by this construction water noises are very largely kept

away from the receiving apparatus, which is preferably located in the lower part of the tank 11, i. e. between the horizontal 55 bulkhead 14 and the bilge of the vessel.

When it is desired to use the fuel oil from one portion of the tank 11, for example from the upper portion, this oil may be pumped into a second tank 15 and used from thence, the upper portion of the tank 11 being filled with sea water. In this way the tank 11 may be kept full all the time and the noise of the swashing around of oil minimized. When it is desired to take in more oil, the 65 sea water is pumped out and the tanks steamed in the usual way, the steam in this case removing the last traces of the salt water, just as in ordinary practice it is used to remove the last traces of oil. Or, if desired, the upper portion of the tank may be left empty.

16 is a cross shaped sound screen and 17, 18, 19, 20 are signaling apparatus placed one in each angle of the cross shaped sound 75 screen.

These signaling apparatus are preferably such as are suitable for sending and receiving or condenser transmitters and receivers of the type herein described.

Applicant has discovered that electric 80 capacities or condensers are very efficient transmitters and receivers of compressional waves in liquids. Such capacities may be of the usual ball or plate form, but are 85 preferably made up of metallic plates or films alternately connected together and separated by a dielectric.

The dielectric is preferably elastic and homogeneous and may be made of india 90 rubber, glass, mica, or paper saturated with paraffine or oil. In fact, any good insulating material may be used.

In the figure, 17 and 18 represent, diagrammatically, condensers having a solid 95 dielectric of mica or glass and 19 and 20 represent condensers having a dielectric composed of paper saturated with oil or oil without paper, and enclosed in boxes 21, 22 to prevent the fluid dielectric from mixing with the oil in the tank 11.

When an alternating voltage is impressed on these condensers, for example by means of the alternating current generator 25 and

- 12
 5 keys 26, 27, the electrostatic attraction between the metallic plates or films of the condensers 19 and 20 compresses the dielectric between the plates and a compressional wave travels out, being transmitted from the condensers to the fluid surrounding the condensers, which in the case shown is the oil in the tank 11, and thence to the water surrounding the vessel.
- 10 A source of continuous current voltage, as shown in 24, is preferably placed in series with the source of alternating current voltage to increase the strength of the signals.
- 15 In this way compressional waves may be emitted from either or both of the condensers 19 and 20 and may be transmitted out in the direction the quadrant of the sound screen 16 faces, in which the condenser is placed.
- 20 The frequency of the compressional waves emitted will depend upon the frequency of the alternating voltage source 25. The compressional waves are preferably either ordinary sound waves of a frequency of about 500 to 1000, or for other work preferably above the limit of audibility. The use of a technical term to express the concept of dilatational waves in material media and of a frequency above that of audibility has been felt for some time, and a number of terms have been proposed. The term anacysms is preferred, as it has priority, having been used by applicant in a report to the U. S. Navy, Dec. 21st, 1912; and it is good Greek, having been used by Aristotle; while "supersonics" has been derided by classical scholars as meaning something quite different, i. e. something sounding above other noises, as a trumpet in battle. I have found that anacysms having a frequency as high as 40,000 are suitable, but frequencies as high as 100,000 or even 200,000 per second may be used.
- 45 Receiving on a condenser submarine signaling apparatus may be accomplished in a number of ways. For example, the condensers 17 and 18 may be charged by the source of continuous voltage 28 and connected to the head phones 29, 30. Sound waves originating from a source ahead of the vessel, on striking the condensers 17 and 18 alter the capacity of the condensers and hence alter the charges on the condensers and hence produce an alternating current in the circuit containing the condensers and the head phones and hence produce a sound in the head phones. If the sound source is located off the port bow of the vessel the intensity of the sound waves received by the condenser 17 will be greater than that received by the condenser 18 and hence the change of capacity in the condenser 17 and the sound produced in the head phone 29 will be greater than that of the condenser 18 and head phone 30. In this way it is possible to tell with sufficient accuracy for most purposes the direction of the sound source, and if it is desired to know the direction exactly the vessel may be caused to turn to port until the sound comes in with equal strength on the head phones 29 and 30 and when this is the case the vessel will be pointing directly to the source of sound.
- 50 In place of receiving in the manner above described, applicant's heterodyne method may be used and this is especially useful when anacysms are used for signaling.
- 55 A suitable arrangement is shown in connection with the condensers 19 and 20, where 25 is a source of alternating current having a frequency of about 40,000 a second; 26 and 27 are signaling keys kept closed for receiving; 24, 24' are sources of D. C. voltage, which are preferably used as giving louder signals but which may be omitted if desired. 31, 32 are primaries of a transformer arranged to act oppositely to each other on the secondary 33, whereby the direction of the sound is more easily determined by noticing which is the stronger.
- 60 When no compressional waves are being received by the condensers 19 and 20, the currents flowing into the condensers create, by means of the primaries 31 and 32, equal and opposite voltages on the secondary 33 and hence do not cause any current to flow through the circuit containing the secondary 33 and the static telephone 34.
- 65 35 is a source of alternating current voltage of approximately a frequency of 39,000 a second and this is connected to the terminals of the static telephone 34 and to the secondary 33, as shown, but does not produce any sound in the static telephone 34 so long as no compressional waves are being received by the condenser 19 and 20, because this frequency of 39,000 is above audibility.
- 70 But on compressional waves arriving from the port quarter and striking the condenser 19, the capacity of the condenser 19 is caused to vary and the voltages impressed by the primaries 31, 32 no longer balance each other and a current of the frequency generated by the generator 25, i. e. 40,000 per second, flows through the circuit 33, 34 and this compounds, in the well known heterodyne method, with the current generated by the generator 35, i. e. 39,000 per second, so as to cause beats of a frequency of 1,000 per second in the static telephone 34, thus producing an audible signal.
- 75 The heterodyne method of receiving in the form above described or in any of the well known forms, is especially well adapted for receiving, because it eliminates disturbing noises, especially water noises, since these are of comparatively low frequency.
- 80 85 90 95 100 105 110 115 120 125 130

It is preferred when frequencies above 40,000 are used to have the oscillator tube described in Letters Patent No. 1,167,366 shortened, or else to work on a frequency 5 that is a multiple of the quotient of the velocity of sound in the material of which the oscillator tube is made, divided by the length of the oscillator tube. Such has been the result of my experience.

10 While any insulator may be used as a dielectric for the condenser receiver-transmitter, the apparatus will be extremely inefficient unless the dielectric is of the same order of density as the liquid in which the 15 condenser is immersed. For example, though air is a good insulator, if the condenser 19 is constructed with an air dielectric the efficiency as a receiver or transmitter will be only of the order of one per 20 cent or less than if the dielectric has a density of the order of unity.

For a similar reason it is advisable that the elasticity of the dielectric should be of the same order as that of the liquid in 25 which the condenser is immersed.

When detecting submarines or similar bodies by echoes, the second high frequency generator 35 is not necessary as the frequency of the generator 25 may be caused 30 to vary regularly between the limits of say 35,000 to 40,000, and hence signals sent out when the frequency is say 36,000 will be received back after reflection from the echo producing body on the condenser receivers 35 at the instant when the generator 25 is generating a frequency of say 38,000, and hence beats will be produced having a frequency of 2,000 per second.

40 In this way the distance of the echo producing body may be determined, by the number of beats produced; since the greater the distance apart the greater the difference in frequency of reflected and generated oscillations.

45 In explanation of the increased efficiency obtained by having the dielectric between the condenser plates constituted of substances having the same order of density, and also preferably of elasticity, as the fluid 50 in which the condensers are immersed, for example sea water, the complete theory has not been worked out, but it is probably due to the fact that when this is the case, and especially when the elasticity and density 55 have such values that there is no difference in phase angle on passing from the fluid to the condenser, the compressional waves are transmitted completely and produce their full effect in varying the capacity of the 60 condenser. While on the other hand, if the density of the dielectric is of a different order of magnitude from that of the oil or sea water the compressional waves are only partly transmitted, being reflected at each 65 layer of the condenser and only penetrat-

ing a small distance and also the phase of the compressional wave may be quite different in different parts of the condenser so that one part may be in compression while another part is in expansion whereby these 70 two parts of the condenser will neutralize each other's effect in producing an indication.

From examination of the following list of materials and densities, 75

Metals	0.53 to 22.4	
Rubber	1.2	
Glass	3.0	80
Mica	3.0	
Paraffined paper	1.5	
Sea water	1.03	
Paraffin oil	0.9	
Air	0.0013	85

it will be seen that the densities of the materials on the left, which include all the standard non-gaseous dielectrics, and the metals which might be used for the conducting sheets of the condensers, are of an entirely different order of magnitude from the density on the right, i. e. that of air. 90

Consequently any standard commercial condenser made of the materials of the left hand column and used while immersed in sea water or oil will be a condenser which has its dielectric and metallic armatures of the same order of density as the medium in which it is operating. While if it has an air or gaseous dielectric, or is used in air or 100 a gas, it will not.

Heretofore condenser signal apparatus for producing and receiving sounds has always been of the latter class, i. e. has either had a dielectric of air or gas, or has been 105 used in a gaseous medium. It has consequently had an extremely low efficiency, for reasons pointed out above in the specification.

Applicant's discovery and invention is 110 that condensers of the first class, i. e. constructed of materials such as those in the left hand column, and most of which are standard commercial articles, may be made very highly efficient producers and receivers of signals if they are immersed in media such as sea water and oil, i. e. media which are, as shewn by the list, of the same order of magnitude as regards density as the condensers themselves. In practice the increase of efficiency has been experimentally 115 found to be in some cases more than 100 times, and to compare favourably with the hitherto generally used microphones. 120

What I claim is:—

1. In the art of submarine signaling, means for producing and for detecting compressional waves in water, comprising a condenser having its dielectric and armatures of materials having their densities of 125 130

the same order of magnitude as water; and said condenser being in operative relation to said water.

2. In the art of submarine signaling, means adapted for the production and the reception of compressional waves in water, comprising a condenser having its dielec-

tric of material of a density of the same order of magnitude as that of water, and its armatures of metal; said condenser being 10 immersed in and in operative relation to said

REGINALD A. FESSENDEN.
